Fig. 6.

Fig. 7.

Fig. 1 is a full scale plan view of a piece of plastic sheet material embodying our new design;

Fig. 2 is a vertical sectional view, taken along line II-II of Fig. 1;

Fig. 3 is a schematic view illustrating the orientation and overlaps of Figures 4, 5, 6 and 7;

Fig. 4 is a view of the upper left portion of a full panel of plastic sheet material taken at a 90° angle from the fragment shown in Fig. 1; and

Figs. 5, 6 and 7 are corresponding views of upper right, lower left and lower right portions of the panel;

the Figs. 4-7 when taken together as illustrated in Fig. 3, show a full panel of the plastic sheet material.

We claim:

The ornamental design for a panel of plastic sheet material or similar article, substantially as shown.
